DESIGN FOR A CORROSION CONTROL EQUIPMENT CABINET

Fredrick J. Ahrens, Oakland, Calif.

Application September 17, 1940, Serial No. 95,131

Term of patent 3½ years

To whom it may concern:

Be it known that I, Frederick J. Ahrens, a citizen of the United States, residing at Oakland, in the county of Alameda and State of California, have invented a new, original, and ornamental Design for a Corrosion Control Equipment Cabinet, of which the following is a specification, reference being had to the accompanying drawing, forming part thereof.

Figure 1 is a side elevational view of a corrosion control equipment cabinet showing my new design;

Figure 2 is a front elevational view; and
Figure 3 is a perspective view showing the device from the front and one side thereof.

The top and rear of the cabinet are plain flat surfaces.

I claim:

The ornamental design for a corrosion control equipment cabinet, as shown and described.

FREDERICK J. AHRENS.
